UNITED STATES PATENT OFFICE.

WILLIS C. HOLLINS AND FRANK P. ARROUSEZ, OF LOS ANGELES, CALIFORNIA,
ASSIGNORS, BY MESNE ASSIGNMENTS, TO ROSENBURG & CO., OF LOS AN-
GELES, CALIFORNIA, A FIRM COMPOSED OF BARNETT ROSENBURG AND
JACK ROSENBURG.

CUT-OUT BOX.

Application filed August 27, 1919. Serial No. 320,123.

To all whom it may concern:

Be it known that we, WILLIS C. HOLLINS and FRANK P. ARROUSEZ, citizens of the United States, both residing at Los Angeles, in the county of Los Angeles and State of California, have invented a new and useful Cut-Out Box, of which the following is a specification.

This invention relates to cut-out boxes, 10 and more especially to that type of cut-out box employing fuses.

An object of the invention is to provide a fire-proof cut-out box of comparatively simple construction.

Another object is to provide a construction in which a single plug is employed for making the electrical connection between two terminals.

Another object is to so construct the sockets for the plugs that, when the plugs are in place in the sockets, contact will be made between the plug and socket terminals over a comparatively large area so that the flow of electric current between the terminals will be a maximum, or equal to that which is provided for by the cross sectional area of the terminal.

Other objects and advantages will appear in the subjoined detailed description.

The accompanying drawings illustrate the invention:

Figure 1 is a side elevation of a cut-out box built in accordance with the provisions of this invention, the near door and tongue being mainly broken away so as to exhibit to view the parts within the casing. A plug is shown inserted in the box.

Fig. 2 is a sectional elevation on line indicated by x^2-x^2 , Fig. 1.

Fig. 3 is an enlarged side elevation of one of the sockets or receptacles and the fuse-supporting clip fastened thereto.

Fig. 4 is a plan section on line indicated by x^4-x^4 , Fig. 3.

Fig. 5 is a plan view of Fig. 1, a portion of the top of the casing being broken away and two sets or pairs of the receptacles being shown in plan section.

Fig. 6 is a side elevation of a modified form of receptacle.

Fig. 7 is a sectional elevation on line indicated by x^7-x^7 , Fig. 6, a plug also being shown in place in the receptacle.

There is provided a casing made of sheet

metal or other suitable fire-proof material and comprising a bottom 1, hinged doors 2 forming the sides of the casing, and ends 3. The doors 2 are channel-shaped and the lower flanges 4 thereof are hinged at 5 to the bottom 1. The upper door flanges 6 are provided with inwardly opening slots 7 through which, when the doors are closed, extend screws 8 provided with wing nuts 9. When the wing nuts are screwed down they engage the door flanges 6 and hold the doors closed. The screws 8 are fastened in longitudinally extending members 10 which constitute upper frame members of the casing and which are provided at their ends with down-turned ears 11 fastened by screws 12, or their equivalents, to the ends 3 of the casing.

The inner marginal portions of the members 10 are bent downwardly and inwardly to form horizontal tongues 13 extending along the side margins of an opening α in the top of the casing. The tongues 13 extend into grooves 14 formed in the longitudinal edges of a socket-supporting member 15 which closes the opening α . The member 15 may be provided with pendent transversely extending partitions 16 which extend between an upper horizontal plate 17 and a lower vertical plate 18 of the support 15. The plate 18 is fastened by screws 49 to brackets 50 which are secured by screws 51 to the casing ends 3. The support 15 is made of any suitable electrical insulating material.

The lower portion of the plate 18 is provided on its opposite faces with any desired number of bus-bars 19 which are fastened to the plate 18 by bolts 20, or their equivalents. The bus-bars, in this instance, are of rectangular construction in plan and to the outer faces of the bus-bars are secured by screws or rivets 21 fuse-supporting clips 22 which are in vertical alignment with other fuse-supporting clips 23 that are fastened by rivets or screws 24 to the outer faces or backs 25 of sockets or receptacles indicated in general by the character 26. The receptacles 26 are positioned in pairs, the adjacent pairs being separated by the partitions 16. One of the receptacles of each pair is positioned on one side of the support 15 and the other receptacle of each pair is positioned on the opposite side of

said support, thus making two opposed series.

In Figs. 1 to 5, each of the receptacles 26 is constructed as follows: A bracket or contact support in the form of a channel-shaped member comprises, besides the back 25 already mentioned, side flanges 27 and an end flange 28. Extending longitudinally inside of the channel-shaped members and bowed outwardly therefrom is a resilient or spring contact member 29 which is free at its lower end and which, at its upper end, is fastened by bolts 30, or their equivalents, to the back 25. The contact member 29 comprises a comparatively long straight member 31 and outwardly slanting members 32, 32' at the ends of the member 31. The member 32' normally engages, or substantially engages, the back 25 so that the lower end of the contact member 29 will be yieldingly held inwardly as well as the upper end thereof.

The end flanges 28 of the receptacles are fastened to the under face of the plate 17 by studs and nuts 33, 34, said studs projecting downwardly from the plate 17 through the flanges 28 and the nuts 34 being tightened up against the lower faces of the flanges 28. The lower ends of the back 25 of the receptacles are secured by studs and nuts 35, 36 to the plate 18, said studs projecting laterally from the plate 18 and through the backs 25 of the receptacles. The nuts 36 engage the outer faces of the backs 25.

The plate 17 is provided with a series of openings 38 through which plugs may be inserted to make electrical contact with the contact members 29. The openings 38 are arranged along a vertical plane passing between the series of receptacles on one side and the series of receptacles on the opposite side, the openings being in fact, centrally over the plate 18 which forms an abutment 39 against which the inner ends of the plugs seat when the plugs are inserted between the two series of receptacles. The plugs may be of any desired construction and one is shown in the drawings merely to make clear the construction and operation of the invention, the plug forming no part of this present invention.

The plug shown in Figs. 1 and 2 of the drawings comprises a body 40 having at its opposite edges contact members 41 adapted to engage the contact members 29 when the plug is inserted between the receptacles of any given pair. The width of the plug, that is the distance between the outer faces 60 of the contact members 41 is slightly greater than the distance between the opposed contact members 29 when the members 32' are engaged with the back 25, so that when the plug is inserted between the opposed contact members said contact members 29 will be

sprung slightly away from one another. Since the contact members 29 are fastened at one end only, when they are thus forced away from one another they can freely elongate, thus permitting the flat members 31 of the contact members 29 to engage the contact members 41 throughout the entire length of said members 31, and thus making good electrical contact because of the relatively large area over which the contact takes place. If it were not for the member 32', it is clear that when the plug is inserted the members 31 would be deflected outwardly more at their lower ends than at their upper ends and consequently a large portion of the members 31 would not engage the plug contact members 41 but would be spaced therefrom.

The leads for the plug are indicated at 42 and said leads are fastened by binding screws 43 to the contact members 41, respectively. Thus when the plug is in place the electrical current can flow from one of the contact members 29 through the adjacent contact member 41, thence through one of the leads 42 to any electrical device to which the leads are connected, thence through the other lead 42 to the other contact member 41, and finally to the other contact member 29. Though but one plug is shown, it is understood that any number may be employed at one time up to the capacity of the box. The box shown in this particular instance accommodates six plugs, and it is understood that a larger or smaller number of receptacles may be employed according to the needs of the customer.

The bus-bars 19 are connected by leads, not shown, to any suitable source of electric current, and said leads may pass through an opening 44 in the bottom 1 of the casing. The fuse-supporting clips 22, 23 are adapted to be electrically connected with each other by fuses, not shown, of any desired construction. Such fuses are well known in the art pertaining to electrical installations and are therefore not shown or described herein, and they form no part of this present invention. When the fuses are thus installed between the clips 22, 23, the electric current will be supplied to the contact members 29, as is readily understood, and the fuses may be readily replaced by others when necessary or desirable. The doors 2 may be swung open for this purpose.

The operation of the invention will be readily understood from the foregoing, for when it is desired to energize any electrical device, the plug connected with said device will be inserted in one of the openings 38 and between two of the contact members 29 so as to supply electric current to said electrical device.

Now referring more particularly to Figs. 6 and 7 of the drawings, the parts therein

which correspond to analogous parts described above in connection with Figs. 1 to 5 are indicated by the same reference characters, and such parts are the elements 25 and 27 forming a channel-shaped member which is thus open at its front. In this instance the contact member is indicated at 45 and is inwardly bowed, instead of outwardly as is the case with the contact member 29. Also the contact member 45 is provided with outwardly slanting members 46, 46' and is provided at one end with a flange 47. A plug 48 is shown in Fig. 7 inserted between the back 25 and the contact member 45, the thickness of the plug being slightly greater than the distance between the back 25 and contact member 45 so that when the plug is inserted in the receptacle it will force the contact member 45 slightly outwardly. The member 46' is normally substantially in contact with a front strip 37 so that when the member 45 is forced outwardly it will be yieldingly held inwardly at its lower end as well as at its upper end in perfect contact with the plug 48 throughout the length of the flat member 31. In this form of the invention the plug 48 is provided with a single lead 52 and the receptacle may be connected with a lead or with a fuse-supporting clip similar to the clip 23 above described.

The invention is not limited in its broader phases to the exact details of construction shown in the drawings and described above, but the invention also includes such changes and modifications as lie within the spirit and scope of the appended claims.

We claim:

40. 1. In a cut-out box, a support of electrical insulation material, a pair of spaced brackets mounted on the support, spring contact members secured at one end to the brackets respectively and bowed toward each other, the other end of the contact members being adapted to loosely engage the brackets so as to yieldingly hold said other end against outward movement, and a fuse-supporting clip mounted on one of the brackets.
45. 2. In a cut-out box, a support of electrical insulation material, a pair of spaced brackets mounted on the support, spring contact members secured to the brackets respectively, and a fuse-supporting clip mounted on one of the brackets.
50. 3. In a cut-out box, a casing having an opening, a plate of electrical insulation fastened in the opening and provided with an opening therethrough, a pair of spaced brackets fastened at one end to the plate and projecting inwardly therefrom, electric contact members mounted on the adjacent faces of the brackets, and fuse-supporting members fastened to the brackets

and projecting from the outer faces of the 65 brackets.

4. In a cut-out box, a casing having an opening, a plate of electrical insulation fastened in the opening and provided with an opening therethrough, a pair of spaced 70 brackets fastened at one end to the plate and projecting inwardly therefrom, electric contact members mounted on the adjacent faces of the brackets, fuse-supporting members fastened to the brackets and projecting from 75 the outer faces of the brackets, a second plate of electrical insulation mounted in the casing, bus bars fastened to the opposite sides of the second plate, and fuse-supporting members fastened to the bus bars in 80 alignment with the fuse-supporting members on the brackets.

5. In a plug receptacle, an electrical insulating member having an opening, a channel-shaped member forming a back and side 85 flanges and mounted on the insulating member with the open side of the channel shaped member turned toward the opening in the insulating member, and an electric spring contact member fastened at one end to the 90 inner face of the back of the channel-shaped member between the flanges and having its opposite end free and adapted to loosely engage the back, said contact member being bowed away from said back to engage a 95 plug inserted in the opening in the insulating member, and means to fasten the opposite ends of the channel-shaped member to a support.

6. In a cut-out box, a casing having an 100 opening, a plate of electrical insulation closing the opening and provided with an opening therethrough, and a pair of spaced 105 brackets fastened at one end to the plate and projecting inwardly therefrom and providing electric contacts on the adjacent faces of the brackets for engagement with an electric plug inserted in the opening of the plate.

7. In a cut-out box, a casing having an 110 opening, a plate of electrical insulating material closing the opening and provided with openings therethrough, a second plate of electrical insulating material in vertical relation to the first plate, electric contacts connected with the first plate on opposite sides of the openings therein, and partitions of electrical insulating material extending transversely of the plates and between said plates.

Signed at Los Angeles, California, this 120
13th day of August, 1919.
